FUSIBLE ELEMENT

John H. Reger, Devon, Conn.

Application March 18, 1948, Serial No. 15,552

6 Claims. (Cl. 169—42)

1

This invention relates to fusible elements or devices and has particular relation to an element or device especially designed for use in fire extinguishers.

An object of the invention is to provide a fusible element or device designed to collapse under heat and pressure and which is so constructed that it retains its shape and size under a considerable degree of pressure.

Another object is to provide an element or device having the characteristics stated and which is constructed to withstand pressure and heat to a predetermined point and then on further heating to collapse suddenly and rather completely.

Other objects and advantages of the invention will become apparent from a consideration of the following detailed description taken in connection with the accompanying drawing wherein satisfactory embodiments of the invention are shown. However, it is to be understood that the invention is not limited to the details disclosed but includes all such variations and modifications as fall within the spirit of the invention and the scope of the appended claims.

In the drawing:

Fig. 1 is an enlarged side elevational view of a fusible element constructed in accordance with the invention;

Fig. 2 is a top plan view of the element, the view being on the scale of Fig. 1;

Fig. 3 is a central vertical sectional view through the element of Fig. 1;

Fig. 4 is a plan view of the element in collapsed or crushed condition;

Fig. 5 is an edge elevational view of the element as shown in Fig. 4;

Fig. 6 is a view similar to Fig. 2 but showing a slight modification; and

Fig. 7 is a side elevational view of the modified structure shown in Fig. 6.

The fusible element of the invention is especially designed for use in a fire extinguisher or the like. One example of such use is disclosed in my parent application Serial Number 682,798 filed July 11, 1946, of which this present application is a continuation in part. Also, my improved fusible element is shown as in use in my copending application Serial Number 15,551, filed March 18, 1948.

Referring in detail to the drawings and at first more particularly to Figs. 1—5, my improved fusible element is generally designated 10. This element 10 comprises a body portion 11 having a recess 12 drilled or otherwise formed therein and

2

extending therethrough or extending substantially therethrough. This recess is in the longitudinal center line of the body and receives a plurality of steel balls 13, or balls of other relatively incompressible material.

As shown, the socket or recess 12 is receiving three of the balls 13 and the latter are in alignment, disposed one on top of the other, and the aggregate of their diameters is the same, or substantially the same, or slightly greater than the thickness of the body 11. Further, it is noted that transversely the recess 12 is of the diameter or substantially of the diameter of the balls 13 whereby when they are located in the recess 15 they are retained in alignment and in relation one on top of the other.

The body 11 includes radially thickened portions 14 and such portions are located about the respective balls 13 whereby the body is radially or laterally strengthened in its portions directly opposite or in radial alignment with the respective balls. Preferably, the body 11 is of Barnabas-Woods material or Cerro Bend. Melting of the body then occurs at a temperature of approximately 150° F.

As will later appear, element 10 is of considerable strength in a direction measured along its length whereby to withstand considerable pressure in such direction without crushing or collapsing. In the use of the element 10, it is customarily held under pressure and such pressure is exerted against the balls while the latter are kept in alignment and so such pressure is withstood by the element, it being understood that the balls are all hard metal or the like.

In any event, the balls are of harder material than the body 11 and have a much higher melting point. The low melting point of the fusible body 11 of the element 10 is desirable especially when the element is used in a fire extinguisher in order that the latter will function or operate at the earliest possible moment after heat is applied to the element whereby the fire extinguisher will function in the early stages of a fire and before the latter has a chance to spread or gain any considerable headway.

As explained in my parent application and my companion application above identified, when the element of the invention is in use it is withstanding the pressure of a spring and also of a fire extinguishing fluid which is kept under pressure. Thus, while in use, the fusible element 10 of the invention is generally under considerable pressure but this pressure is exerted through the incompressible aligned balls 13. As long as

these balls remain in alignment, the pressure is transmitted from one to the other of the balls and they provide an incompressible column.

Assuming that the present element is in place in a fire extinguisher and that the latter is loaded, on heat reaching the present element to sufficient degree, the body 11 softens rapidly. At this time, the body will be under considerable pressure as suggested above and as the body softens the balls 13 are permitted to go out of alignment or move out of alignment and they do move laterally or radially.

As this occurs, there is a very rapid collapse of the element 10. Thus, the element may very rapidly collapse from the height of Figs. 1 and 3 to substantially that shown in Fig. 5 as the balls 13 move radially or laterally of one another and come into a side-by-side relation in the same plane (see particularly Figs. 4 and 5). This is true since when the balls move off of one another or out of the column or arrangement, they no longer provide the rigid support to withstand the pressure on the element and they permit of lateral movement of the balls and the element collapses rather suddenly and thoroughly.

Where the element is used in an extinguisher and the extinguishing fluid is passing in the vicinity of the element, the amount of collapse of the element will depend to some extent on the rapidity with which the element is cooled by the escaping fluid or the fire extinguishing fluid being discharged. Generally, the element will collapse to approximately one-third its original height, in which instance all three of the balls 13 will be at the same level or in the same plane and in a side-by-side relation as suggested in Figs. 4 and 5 wherein the collapsing body of the element is designated 15.

Thus, it will be understood that the present element remains extremely rigid to any pressure applied longitudinally of it until the balls 13 are permitted to move laterally with respect to one another. Then the body 11 of the element being softened by heat, the balls are not retained against lateral movement and slipping off one another leave the softened body 11 to take the above mentioned pressures. Thereupon, the body suddenly and completely collapses so as to permit a fire extinguisher to function. For example, this collapse of the element in my applications above mentioned permits the opening of a valve.

Figs. 6 and 7 show a slight modification of a fusible element and in said figures the fusible element is generally indicated at 16. This element includes a body 17 having a recess or opening 18 drilled or otherwise formed therein and extending therethrough or extending substantially therethrough. This recess or opening 18 of Figs. 6 and 7 corresponds with the recess or opening 12 of Figs. 1, 2 and 3 and is for the same purpose. Thus, opening 18 is shown as receiving three relatively hard balls 19 and the recess transversely is substantially of the diameter of the balls whereby the latter are retained in position one on the other.

The aggregate diameters of the balls 19 is substantially the same as the overall height of the body 17 or the length of the recess 18. Body 17 includes flat lower and upper ends 20 and 21 and for a distance slightly upwardly from the lower flat surface 20 the body 17 is of uniform diameter and then it tapers inwardly toward its upper flat surface 21, as at 22. Thus, the body is of less diameter toward its upper end or surface 21.

The element 16 of Figs. 6 and 7 will be used in the manner in which the element 10 of the first figures is used. Thus, the element 16 will withstand a great pressure applied longitudinally to it, such pressure being merely transmitted by the incompressible balls 19. However, on softening of the body 17 of the element whereby said balls may move off one another and into a lateral relation, pressure applied as described will cause a sudden and complete collapse of the body 16 resulting in the balls being disposed in side-by-side relation as illustrated in the body 15 (Figs. 4 and 5) and which body represents the collapsed body 11 of the element 10.

From the above description, it will be clear that I have provided a fusible element so constructed as to withstand a tremendous compressive force applied to it in the direction of its length or in a manner to press one of the incompressible balls 13 or 19 of Figs. 3 and 7 against the others thereof. However, on softening of the body material of either of the elements 16 or 10 so that the balls may shift laterally or out of alignment, then the applied pressure on the heat softened body of the element will result in rapid and rather complete crushing or collapsing of such body.

Having thus set forth the nature of my invention, what I claim is:

1. A fusible element for use in a fire extinguisher, said element comprising a body of fusible material having a recess extending substantially entirely therethrough, a series of balls disposed in said recess, the diameter of said recess and said balls being such that the latter are disposed one on the other in said recess, said recess being of substantially uniform diameter and opening through at least one end of said body whereby all of said balls may be placed therein from said end of the body and the collective diameters of said balls being substantially equal to the depth of said recess.

2. The element as in claim 1 wherein said balls are of a substantially incompressible material having a heat softening point materially higher than that of said body.

3. A fusible element for use in a fire extinguisher, said element comprising an elongated one-piece body of fusible material having a recess extending longitudinally substantially entirely therethrough, a series of balls of substantially non-fusible material in said recess, said recess and said balls of such diameter that the latter are disposed one on the other in said recess, said recess being of substantially uniform diameter and opening through at least one end of said body whereby all of said balls may be placed in the recess from said end thereof, and the collective diameter of said balls being substantially equal to the length of said recess.

4. A fusible element for use in a fire extinguisher, said element comprising a body of fusible material having a recess extending substantially entirely therethrough, a series of balls disposed in said recess, the diameter of said recess and said balls being such that the latter are disposed one on the other in said recess, the collective diameters of said balls being substantially equal to the depth of said recess, and said body radially thickened in its portions radially of the respective balls.

5. A fusible element for use in a fire extinguisher, said element comprising a body of fusible material having a recess extending substantially

entirely therethrough, a series of balls disposed in said recess, the diameter of said recess and said balls being such that the latter are disposed one on the other in said recess, the collective diameters of said balls being substantially equal to the depth of said recess, and said body externally tapered for a substantial portion of its length through one of its ends whereby such end is of less diameter than the other end of the body.

6. A fusible element for use in a fire extinguisher, said element comprising a body of fusible material having a recess extending substantially entirely therethrough, a series of balls in said recess, the diameter of said recess and said balls being such that the latter are disposed one on the other in said recess, the collective diameters of said balls being substantially equal to the

depth of said recess, said body having substantially flat ends, and said body of a constant diameter in one end portion and then tapered inwardly throughout its length to its other end whereby such other end is of substantially less diameter than the first mentioned end.
